CHECKERWORK FOR HOT-BLAST STOVES

John P. Foley, Lorain, Ohio, assignor to National
Tube Company, a corporation of New Jersey

Application December 29, 1937, Serial No. 182,323

4 Claims. (Cl. 263—51)

This invention relates to the construction of the checkerwork for hot-blast stoves and, more particularly, to inserts therefor.

Checkerworks for hot-blast stoves ordinarily comprise an integrated structure of vertically extending overlapped bricks which provide a series of vertically extending rectangular or square flues or passages. The heat absorbing and transferring quality of the stove is largely determined by the amount of surface of the flue defining bricks in contact with the gases passed therethrough. This can be increased by decreasing the size of such flues with the attendant disadvantages of increasing the cost of the checkerwork,

10 by the amount of surface of the flue defining bricks in contact with the gases passed therethrough. This can be increased by decreasing the size of such flues with the attendant disadvantages of increasing the cost of the checkerwork, 15 since a larger number of bricks are required and also more time is needed to lay them. To overcome this difficulty the use of inserts in the flues has been resorted to to increase the capacity of the stove. In accordance with the teaching of 20 the present invention, inserts of improved design are provided which greatly increase the capacity of the stove without any change in the general structure thereof.

It is accordingly an object of the present invention to provide a hot-blast stove checkerwork having a greater heat transferring capacity than was heretofore possible.

It is another object of the present invention to increase the capacity of hot-blast stove checkerwork without changing the fundamental structure thereof or increasing its cost.

It is a further object of the present invention to provide an insert for hot-blast stove checkerwork of improved design and heat exchanging capacity.

A still further object of this invention is the provision of a checkerwork having the novel constructions, combinations and arrangements of parts shown in the drawings, to be more particularly described hereinafter and to be particularly pointed out in the appended claims.

My invention consists in the provision of a refractory checkerwork having a series of vertical passages formed therein with the ends of the 45 bricks of the checkerwork in overlapping or interlocking engagement so as to integrate the structure, and providing in the vertical passages or flues vertically extending superposed corrugated cylindrical inserts which alternately contact opposite sides of the passage or flue to maintain the inserts in superposed position and form a tortuous passageway for the gases passed therethrough.

Referring to the drawings forming part of this specification:

Figure 1 is a horizontal section showing a hot-blast stove having a conventional checkerwork arrangement embodying the inserts of my invention;

Figure 2 is a fragmentary vertical section of one of the flues of Figure 1 showing the disposition of the inserts of my invention therein;

Figure 3 is a horizontal section taken on the line III—III of Figure 2;

Figure 4 is a horizontal section on the line 10 IV—IV of Figure 2; and,

Figure 5 is a perspective view of the checkerwork insert of my invention.

Referring more particularly to the drawings, the numeral 2 designates the cylindrical metal 15 shell of a hot-blast stove which is provided with the usual refractory lining 3. The stove shown has a side combustion chamber 4 and a checkerwork chamber 5 which are formed in the refractory lining 3, a solid wall 6 separating the combustion chamber 4 from the checkerwork chamber 5. The combustion chamber 4 is provided with a removable lining wall 7.

The checkerwork chamber 5 is filled with checkerwork 8 composed of rectangular refractory bricks 9 which are laid in overlapping relation to form a plurality of vertical flues or passages 10. The flues 10 extend from a point a short distance above the bottom of the stove to a point adjacent but below its top.

Within the vertical flues 10 of the checkerwork 8 are superposed the inserts 15 of my invention, which extend vertically within the flues 10 and are supported at the lower end of the vertical flues 10 in any suitable manner.

The inserts 15 are composed of a refractory material or other suitable substance, and are of a generally cylindrical shape with alternate corrugations on two opposing sides. That is, the corrugations, shown at 16, do not extend entirely 40 around the inserts so that a portion on either side thereof has a straight surface 17 disposed between the corrugations. The alternate corrugations 16 on opposite sides of the inserts 15 are such that all transverse cross-sections of the 45 inserts 15 are circular and of equal diameter. According to a preferred embodiment the corrugations 16 are terminated a short distance from each end of the inserts 15 to leave plain cylindrical sections 18 at either end thereof.

The inserts 15 and their corrugations are of such size that they will fit within the square flues 10 contacting the walls thereof at points adjacent two opposite corners. When placed within the flues 10 alternate inserts 15 are dis-

posed at an angle of 90 degrees with respect to their straight sides 17 and corrugations 16. Thus, although the cross-sectioned area of the opening in the flues 18 remains constant through its length, this disposition of the corrugations shifts a portion of this total opening area alternately from one pair of oppositely disposed corners to the other pair of oppositely disposed corners.

10. It will be readily seen that the corrugations 16 of the inserts 15 of my invention greatly increase the heating surface of the insert over that of conventional inserts. Moreover, due to the corrugations 16 being placed only on two sides 15 of the inserts 15, and their novel disposition within the flues 18 causing a shifting of the flue area or openings, the gas or blast therethrough follows a tortuous path giving a scrubbing effect to the gas or blast in its passage therethrough.

15. Also, the shafts or wells in each corner are reduced to a minimum and since the cross-sectional area of the openings is kept constant, the possibility of jets of the blast or gas by-passing available heating surface is largely eliminated.

20. While I have shown and described a specific embodiment of my invention, it will be understood that I do not wish to be limited exactly thereto, since various modifications may be made within the scope of the following claims.

25. I claim:

1. In a hot-blast stove, checkerwork having vertically extending flues therein and substantially cylindrical superposed inserts within said

flues, said inserts having longitudinally extending alternate plain and transversely corrugated wall portions at opposite sides thereof.

2. In a hot-blast stove, checkerwork having vertically extending flues therein and substantially cylindrical superposed inserts within said flues, said inserts having alternate longitudinally extending plain and transversely corrugated wall portions, the successive inserts in said flues having their plain portions in alignment with the 10 corrugated portions of the preceding insert.

3. In a hot-blast stove, checkerwork having vertically extending rectangular flues therein and substantially cylindrical superposed inserts within said flues, said inserts having alternate longitudinally extending plain and transversely corrugated wall portions, the successive inserts contacting alternately the walls of said flues at points adjacent opposite corners of said rectangular flues.

4. In a hot-blast stove, checkerwork having vertically extending square flues therein and superposed inserts of circular transverse cross-section in said flues, said inserts having alternate longitudinally extending oppositely disposed plain 25 and transversely corrugated wall portions, the successive inserts having their plain portions in alignment with the corrugated portions of the preceding insert, the corrugated portions of said inserts contacting the walls of said flues at points 30 adjacent opposite corners of the said square flues.

JOHN P. FOLEY.
